ATTORNEY

BY

UNITED STATES PATENT OFFICE.

CHARLES J. AULBACH, OF PASSAIC, NEW JERSEY, ASSIGNOR TO PASSAIC METAL WARE COMPANY, OF PASSAIC, NEW JERSEY, A CORPORATION OF NEW JERSEY.

CONTAINER.

Application filed August 11, 1926. Serial No. 128,521.

An object of my invention is to provide a container with one or more projections or ears by means of which the container may be retained or secured in a desired position. 5 a further object being to secure such projection or ear to the container between the container body and a head or end thereof by the seaming together of said body and end and without requiring the use of other 10 securing means, thus providing a secure and inexpensive means of securing said ends to containers.

In carrying out my invention I provide a container or can body, a head, or end there- 15 for adapted to be seamed thereto, and a retainer having a portion located between the marginal portions of the body and the head in such position that when the body and head are seamed together, as in an ordinary 20 can-body seaming machine, the retainer will be secured by the seaming.

My invention further comprises novel de- 25 tails of improvement that will be more fully hereinafter set forth and then pointed out in the claim.

Reference is to be had to the accompa- 30 nying drawings forming a part hereof, wherein

Fig. 1 is a side view of a container em- 35 bodying my invention;

Fig. 2 is a partly broken plan view of the container body, the cover being omitted;

Fig. 3 is a section on line 3, 3, in Fig. 2;

Fig. 4 is a perspective view illustrating my 35 improved retainer to be secured to the container;

Fig. 5 is a sectional detail illustrating a 40 step in producing my improvement, showing the retainer upon an end of the container body;

Fig. 6 is a similar view illustrating an- 45 other step showing the head or end in position;

Fig. 7 is a similar view showing the parts 45 secured together by single seaming;

Fig. 8 is a similar view illustrating an end 50 portion of the retainer as bent outwardly from the container body in position for use as a projection or lug;

Fig. 9 is a view substantially similar to 55 Fig. 7, showing the parts secured together by double seaming; and

Fig. 10 is a sectional detail illustrating a 60 modified form of the retainer.

Similar numerals of reference indicate 55 corresponding parts in the several views.

The numeral 1 indicates a container or box which may be in the form of an ordinary tin can, and at 2 is a head or end at one end of the container body, which parts may be secured together by seaming, such as is customary in seaming the bodies and heads or ends of tin cans, either by single seaming or double seaming. At 3 is indicated a 60 cover for the open end of the container and 65 which may be of any suitable or usual detachable type.

At 4 is indicated my improved retainer which, in Figs. 1 to 9, is represented as a 65 strip of suitable material such as metal, ex- 70 tending across the container and located against or adjacent to its head or end 2, with end portions of the retainer at 4^a ex- 75 tending from the container, in the nature of projections or ears which may be provided with holes 5 for securing the parts to an object. The retainer strip 4 adjacent to its ends is shown bent into hook-like form at 4^b with the projecting portions 4^a substan- 80 tially at right angles to the plane of the strip. The hook-like portions 4^b are adapted to receive the edge portion of body 1 at 85 an open end so that the main or middle portion of the strip 4 may be located within the container body.

When the parts are to be assembled the strip 4 will be placed against an open end of the container body, the edge portion of which will enter the hook-like portions 4^b of the retainer, and the head or end 2 will be 90 placed in position against the same open end of the body and against the strip 4, with the retainer at the junction of the body and the head, as illustrated in Fig. 3. The container body 1 may be placed on end, as 95 on a usual mandrel in a seaming machine, (not shown), with the retainer strip 4 in the position stated and the projecting portions 4^a extending along the sides of the body, as illustrated in Fig. 5. According to 100 the next step the head or end 2 is placed upon the corresponding end of the body 1 and its offset portion 2^a rests over the end of the body and over the strip 4, as illus- 105 trated in Fig. 6. With the parts in the last named position the projecting marginal portion 2^b of the head or end 2 may be seamed, as in a seaming machine, to secure

the head to the body 1, whereupon part of the seamed portion 2^b will bear against the outer parts of the hook-like portion 4^b of the retainer while the portions 4^a of the retainer remain substantially parallel with and against the adjacent outer surface of body 1, as illustrated in Fig. 7. With the parts 4^a of the retainer extending along the sides of the body 1, as in Figs. 5, 6 and 7, during the time of seaming the body 1 and the head 2 together, said parts do not interfere with the seaming tools of the seaming machine, which tools can operate around the edge portion 2^b of the head 2 and outside 15 of the hook-like portions 4^b of the retainer without interference therefrom. After the parts have been seamed together, as illustrated in Fig. 7, the portions 4^a of the retainer may be bent outwardly from the container body in the nature of projections or ears, through which screws or nails may be driven for securing the body to a support by means of said projections or ears.

In Fig. 9 the body 1 and the head or end 2 are attached together by double seaming, and in this instance the portion of the retainer 4 projecting beyond the body, such as at 4^b and 4^a, is of sufficient length to permit the same to be folded in with the double seaming 2^c, with sufficient of the portion or portions 4^a of the retainer extending outwardly to be bent into the form of projection or lug 4^a.

While I have so far described the retainer 4 as provided with two hook-like portions 4^b and of such dimension as to extend across the interior of the body 1 to provide two hook-like portions 4^b on the retainer strip for engagement with the edge of the body 1, it will be understood that the retainer need not extend across the body 1 and may be provided with a single projection or ear 4^a on one side only. Such construction is illustrated in Fig. 10. Instead of having the material of the retainer rest against the head or end 2 the inner portion of the retainer may extend along an inner side of the wall of the container, as indicated at 4^c, and the head or end 2 may be single seamed 45 to the container to secure the retainer, as illustrated in Fig. 10, or may be double seamed in the manner described with respect to Fig. 9.

By means of my improvement the re-

tainer is securely attached to the container body between the latter and its head or end without danger of becoming displaced, so that the container may be provided with one or more outwardly extending projections or ears 4^a for securing the retainer as before described. The construction described is advantageous in that no solder or rivets are required to secure a projection or ear to a container, dispensing with rivet holes and danger of solder becoming loosened and releasing a projection or ear. The cost of manufacture is reduced and an efficient container of the character set forth is provided.

While I have illustrated and described the container as comprising a body and a head or end secured together by double seaming and have set forth such construction as advantageous in securing the retainer to the container, whereby the use of solder or rivets for securing projections or ears to containers may be dispensed with, it will be understood that my invention is not limited to securing a retainer to a container or can body where the joint between the body and head or end is made by seaming. My improved retainer can be located in the position described, at the junction between a container body and its head or end, in which the parts are secured together by soldering in a well known way, in which instance my improved retainer will be secured at the junction between the body and its head or end with a projection or ear 4^a exterior to the container where a so-called soldered as distinguished from a so-called seamed container is desired.

Having now described my invention what I claim is:

A container comprising a body and a head and having a retainer comprising a strip extending within the body across the head and having spaced hook-like portions receiving an end of the body, said retainer having projecting portions without the body, the head having a marginal portion seamed to the body outside of the latter and outside of adjacent portions of the retainer, the retainer having projecting portions extending beyond the container for securing the container to a support.

CHARLES J. AULBACH.
